UNITED STATES PATENT OFFICE.

LYLE G. CHASE, OF PLAINFIELD, NEW JERSEY, ASSIGNOR TO YARNALL-WARING COMPANY, OF PHILADELPHIA, PENNSYLVANIA, A CORPORATION OF PENNSYLVANIA.

SKIMMER INLET FOR BOILERS.

Continuation of application Serial No. 254,367, filed September 16, 1918. This application filed March 17, 1924. Serial No. 699,778.

My invention relates to skimmers for use in cleaning boiler water, used in conjunction with settling systems to remove suspended matter from the water.

5 The purpose of my invention is to provide a novel form of inlet that is at once well adapted to meet the needs of service and easy and inexpensive to manufacture.

A further purpose is to have efficient 10 skimming whatever the water height within the range of water height that may be met in practice by having relatively spaced split pipes branch upwardly through the water to the steam space from an eduction main 15 beneath the water. The pipes may extend vertically or at any angle.

A further purpose is to have the splits in the pipes progressively wider toward the top.

20 A further purpose is to relatively stagger the direction of presentation of the splits. Further purposes will appear in the specification and in the claims.

I have preferred to illustrate my invention by but one main form, with a minor modification, and have selected a form that is efficient in operation and which illustrates particularly well the principles involved.

This application is a continuation of the 30 subject matter referred to in my application No. 254,367, filed September 16, 1918.

Figure 1 is a longitudinal section of one form of boiler with one of my skimmers in position.

35 Figure 2 is a section of Figure 1 to enlarged scale taken upon the line 2-2 and showing means to settle out dirt removed from the boiler.

Figure 3 is a broken elevation of a portion 40 of the skimmer system showing top plan views of the skimmer pipes.

Figure 4 is a side view of one of the split pipes.

45 Figure 5 is an end view of Figure 4.

Figure 6 is a broken elevation of a portion of the skimmer system modified in minor detail and showing end views of the skimmer pipes.

In the drawings similar numerals indicate 50 like parts.

Describing in illustration and not in limitation and referring to the drawings,—

I show in Figures 1 and 2 my skimmers installed in a boiler 15. The eduction main

16 extends longitudinally of the boiler just 55 above the fire tubes 17 and below the water level within the boiler and carries the skimmer inlet pipes 18.

The skimmer inlet pipes branch from long-sweep T's 19 of the eduction main and 60 extend upwardly into the steam space 20 above the water. They are slit longitudinally along diametrically opposite lines at 21 throughout a vertical height covering the 65 range of variation of water level within the boiler and preferably the sides of the slits are progressively spread toward the upper ends, thus properly functioning whatever the water level.

The skimmer inlet pipes are conveniently 70 made by sawing sections of pipe longitudinally to form the slits. The split sections may be permanently sprung open to desired spread or may be sprung over a wedge 22 as shown in the illustration, this clamped 75 wedge being held to place by a suitable cotter pin 23.

By splitting and spreading the pipe the outer end of the pipe section remains open except for the spreader bar and retaining 80 pin leaving half the cross-section of the pipe interior on each side of the bar for flow in at the end. This gives sufficient cross-section throughout for uninterrupted 85 flow in each half section of the pipe including the outlet opening at each side of the bar. This provides uniformity and smoothness of movement and the same contour of engaging surfaces (i. e., the interior wall of half the pipe) difficult otherwise of attainment. It is subject of course to interruption by transverse lines of flow through the slits. At the same time the method of manufacture is simple and inexpensive and leaves a terminal at one end which is unslotted and unspread and which can readily be threaded for engagement within or upon suitable fittings.

The splits of the adjacent pipes are preferably presented relatively at right angles 100 to each other to afford a somewhat better diversity of inlet direction. Obviously too the split pipes may be relatively in line as indicated in Figures 1 and 2 or not, according to circumstance and the particular arrangement giving best surface skimming.

It is advantageous to have the T's 19 "long-sweep", in order that there may be

minimum chance for collection in them of dirt skimmed from the boiler, as well as minimum resistance to the circulation used in automatic skimming, and the arrangement 5 of Figure 6, with other advantages, gives particularly easy sweep at the T's.

The settling drum 24 is connected on one side through valve 25 by pipe 26 to the eduction main and on the other side by pipe 27 10 and valve 28 into the bottom of the boiler. Radiation surfaces 29 are preferably provided around the pipe 26, around the settling drum and around the pipe 27, the rapidity of automatic circulation from the 15 skimmer pipes into the eduction main and thence to the settling drum and from the settling drum back to the boiler depending upon relatively low temperature in the vertical portion of the circuit outside of the 20 boiler, and rapidity of settling in the drum increasing with lowness of temperature in the drum.

The drum is periodically blown off at the blow-off pipe 30.

25 In view of my invention and disclosure, variations and modifications will doubtless become evident to others skilled in the art, to meet individual whim or particular need, and I claim all such in so far as they fall

within the reasonable spirit and scope of my 30 claims.

Having thus described my invention, what I claim as new and desire to secure by Letters Patent is:—

1. An inlet device for a skimmer system 35 which consists of a longitudinally extending collecting conduit and a plurality of spaced upwardly extending slotted pipes connecting therewith, having the slits extending parallel to the axes of the pipes and in different directions in adjoining pipes.

2. An inlet device for a skimmer system 40 which consists of a longitudinally extending collecting conduit, a plurality of upwardly extending pipes connecting therewith, slotted longitudinally of the pipes, the walls of said splits being separated to cause the adjoining edges of the slits to diverge and the slits opening in different directions in adjoining 45 pipes.

3. An intake device for a skimmer system comprising a horizontal conduit and a plurality of upwardly extending inlet devices 50 connected therewith at intervals along the conduit, each having one or more side openings and the openings in adjoining sides facing in different directions.

LYLE G. CHASE.
